UNITED STATES PATENT OFFICE.

GEORG ULLRICH, OF MAGDEBURG, GERMANY, ASSIGNOR TO FRIED. KRUPP AKTIEN-
GESELLSCHAFT GRUSONWERK, OF MAGDEBURG-BUCKAU, GERMANY.

MAGNETIC SEPARATOR.

Application filed March 18, 1921. Serial No. 453,540.

To all whom it may concern:

Be it known that I, GEORG ULLRICH, a citizen of the German Empire, residing at Magdeburg, Germany, have invented certain new and useful Improvements in Magnetic Separators (for which I have filed application in Germany, July 11, 1919; Spain, June 4, 1920; Italy, June 16, 1920; Holland, June 16, 1920; England, June 18, 1920; 5 Czechoslovakia, June 22, 1920; Portugal, June 30, 1920; Australia, July 10, 1920; France, June 30, 1920; Sweden, March 22, 1919, Patent No. 47,788; and Norway, March 26, 1919, Patent No. 31,749), of which 10 the following is a specification.

My invention relates to magnetic separators and more especially to separators of the revolving ring type. Its particular object is to increase the efficiency and to lessen the 20 cost of manufacture of such apparatus. In magnetic separators of the type aforesaid and particularly those having several magnetic separating zones, the use of sloping feed devices for conveying the raw material 25 to the separator causes certain difficulties in the manufacture thereof. Thus the lower or stationary poles have to be bevelled and stepped to correspond to the stepped rings arranged above them, otherwise the stepped 30 rings would be at a different distance from the lower poles at each point where the particular part of its operative edges is in the field. The stepped form of the lower poles also necessitates the feeding device being 35 shaped to correspond thereto. This construction makes the manufacture of the separator considerably expensive and furthermore the poles when thus stepped are only suited to a single position of the feeding 40 device.

In order to adapt the lower poles to a number of various sloping positions of the feeding device it has been proposed to divide the lower poles into a number of pole 45 pieces corresponding in number to the number of the rings in the revolving ring and to render them adjustable relatively to one another. If however the speed at which the material is fed to the separator is to be 50 suited to the particular character of one sort of material and if the inclination of the feeding device be altered accordingly, a readjustment of all the zones is necessary, as the distance of the upper surface of the material from the pole pieces or rings forming 55

the different zones changes with every change of position of the feeding device, such readjustment necessitating the stoppage of the separator, besides being difficult and requiring much time.

According to the present invention magnetic separators of the revolving inductor ring type are provided with means whereby the disadvantages stated above are overcome, such means consisting in an arrangement of the several parts of the separator so that the frame, the lower stationary poles, the revolving annular magnet, and the feeding device for the material can be tilted as a whole without any relative displacement 60 of the said parts taking place; in order therefore to alter the position of the feeding device for the material it is only necessary to slightly incline the frame of the separator, which operation can be carried out 65 while the apparatus is working. The rings and the pole pieces do not require to be adjusted. The lower pole pieces do not need to be bevelled off when the feeding device is set obliquely and in consequence thereof 70 the stepping of the lower pole pieces is not necessary either as they are at the same distance from the feeding device at every point of the particular part of their operative 75 edges which happens to be in the magnetic field. The tilting may be conveniently effected about the driving shaft of the separator, thereby preventing the driving belt or 80 belts from being interfered with or their tension disturbed by the tilting of the frame. 85 In order to enable the position of the devices for carrying away the magnetic material to be also altered during the tilting of the frame of the separator, they may be connected to the separator itself or to the device which supplies the raw material to and 90 carries the non-magnetic material away from the apparatus in such a manner that they take part in the various inclinations 95 of the separator.

In the drawings affixed to this specification and forming part thereof two modifications of an apparatus embodying my invention are illustrated diagrammatically by way of example. In the drawings—

Fig. 1 is a side elevation, partly in section, of one modification, and

Fig. 2 is a plan of another modification.

Referring to the drawings, the magnetic frame 1 together with the lower poles 2, 3, 110

4, 5, the annular magnet 8 provided with two knife edges 6, 7 and the shaking table 9 which feeds in the raw material are arranged so as to be capable of being tilted about the 5 pin 10. In the example shown this pin 10 lies in the axis of the driving shaft 11 so as not to interfere with the tension of the driving belt when the separator is tilted which arrangement also enables the separator to be 10 tilted while it is working, by means of the hand wheel 12. The annular separator illustrated has two magnetic fields, each comprising two zones 2/6, 3/7 and 4/7, 5/6. In order to allow of regulating the strength of the 15 fields the annular magnet 8 may be made adjustable in a vertical plane on its axis 13. To adjust the different zones the pole pieces 2, 3, 4, 5 may be moved vertically. The knife edges 6, 7 might also be arranged on separate pole pieces adjustably attached to the 20 magnet 8.

The operation of the separator is as follows:

The raw material supplied into the hopper 25 14 falls on to the shaking table 9 and passes into the magnetic fields formed by the knife edges 6, 7 and the pole pieces 2, 3. The most strongly magnetic ore is attracted into the zone 2, 6 and the weaker magnetic ore into the zone 3, 7. The mixture of raw material 30 remaining on the table then passes into the magnetic field formed by the knife edges 6 and 7 and the pole pieces 4 and 5 in which such weakly magnetic material as is still present, is separated into two kinds in the zones 4/7 and 5/6. The magnetic particles 35 attracted by the knife edges 6, 7 are carried out of the magnetic fields by the revolving magnet 8 and are then collected separately, while the non-magnetic material passes on 40 through the separator on the shaking table 9 and falls off at the end.

In order to enable the magnetic material which has fallen off the annular magnet 8 to

be carried away at a speed which is about 70 equal to that of the non-magnetic material, the chutes for carrying away the magnetic material are built on to the table 9 as shown in Fig. 2, the said chutes are compelled to follow every change in the position or tilt of 75 the table 9. When the annular magnet rotates in the direction of the arrow x the magnetic materials separated in the zones 2/6, 3/7, 4/7 and 5/6 and carried away by the annular magnets are correspondingly collected by 80 the chutes 15, 16, 17, 18 and pass off therein in a direction parallel to the non-magnetic material. By the aforesaid combination of the chutes 15, 16, 17, 18 with the table 9 a convenient survey over the material in its 85 various degrees of separation as it is moving away is provided, so that in the event of defective separation suitable measures may at once be taken.

In the position shown in Fig. 1 the table 9 90 is shown horizontal. If however the speed of the material on the table and in the chutes is to be increased, the table is tilted in the direction in which the material travels. The chutes 19 take up the weakest magnetic particles which are the first to fall from the annular magnets.

I claim:

A magnetic separator comprising in combination, a support, a substantially vertical 95 shaft carried in said support, an annular magnet on said shaft, a plurality of stationary lower poles on said support underneath said magnet, a substantially horizontal driving shaft in gear with the lower end of said vertical shaft, a conveyor on said support intermediate said magnet and said poles and means for tilting said support about said horizontal shaft.

In testimony whereof I affix my signature.

GEORG ULLRICH.
